United States Patent Office

Des. 221,456
Patented Aug. 17, 1971

221,456

TOY WHEELED VEHICLE OR THE LIKE

Richard E. Henderson, Huntington Beach, Calif., assignor
to Mattel, Inc., Hawthorne, Calif.

Filed June 8, 1970, Ser. No. 23,345

Term of patent 14 years

Int. Cl. D21—01

U.S. Cl. D34—15

Fig. 1

Fig. 3

Fig. 2

FIG.4

FIG.5

FIG.6

FIG. 1 is a perspective view of a toy wheeled vehicle showing my new design; and

FIG. 2 is a left side elevational view, the right side being a mirror image thereof; and

FIG. 3 is a front elevational view thereof; and

FIG. 4 is a top plan view thereof; and

FIG. 5 is a rear elevational view thereof; and

FIG. 6 is a bottom plan view thereof.

I claim:

The ornamental design for a toy wheeled vehicle or the like, as shown and described.
